SMOKELESS POWDER TESTER

Clarence N. Hickman, Jackson Heights, N. Y., and Arthur J. Dempster, Chicago, Ill., assignors, by direct and mesne assignments, to the United States of America as represented by the Secretary of the Navy

Application September 2, 1943, Serial No. 501,002

5 Claims. (Cl. 73—35)

1

This invention relates to devices for testing explosives, and more specifically to a device for producing samples of explosives which have been partially burned under specified conditions.

An object of this invention is to provide a device for producing samples of explosives which have been partially burned under conditions similar to those encountered in actual use. By the use of this invention, it is possible, for example, to detect by means of the pitted appearance of the partially burned powder grains, flaws in the powder which result in an uneven rate of burning.

Another object of our invention is to provide a device for testing explosives intended for use in jet propelled devices, by partially burning samples of such explosives under controlled pressures so as to approximate closely conditions existing in the intended use of the explosives. Although the device may be used to particular advantage in testing explosives for use in jet propelled devices, we do not intend that its use be limited to such explosives.

A further object of our invention is to provide a device of the character described which will operate without danger of damage to the device, by reason of its inclusion of a pressure limiting shear ring which will give way in case of excessive pressures within the device.

A further object of our invention is to provide a device of the character described which is simple in construction, easy to manufacture, and inexpensive.

These and other objects of the invention may be better understood by reference to the accompanying drawing, in which

Fig. 1 is a longitudinal cross sectional view of one form of the new powder testing device;

Figs. 2 and 2A are plan and side views, respectively, of the shear ring employed in the device;

Figs. 3 and 3A are plan and side views, respectively, of the perforated disc employed in the device, and

Fig. 4 is a detail view of the piston partly cut away so as to show how its sections are screwed together.

In the drawing, the numeral 10 designates a cylinder which is threaded internally at each end. A threaded base plug 11 is screwed into the lower end of the cylinder, the base plug having an axial opening extending therethrough. In the upper end of cylinder 10 is threaded a cylindrical nozzle holder 12 which extends out beyond the end of cylinder 10, a short distance. A recess is formed in the interior of the lower end of nozzle holder

2

12, and in this recess is fitted a shear ring 13 which has an inwardly extending portion 13a serving to retain a nozzle 14 against movement out of the nozzle holder by engaging an outwardly lower portion 15 of the nozzle.

Within the cylinder 10 is a piston having a lower portion 16, an upper portion 17, and a reduced central portion 18 which is surrounded by a pipe spacer 18a, the purpose of which will be explained below. Shoulders 16a and 17a are formed on the piston at the ends of its central portion 18. As shown in Fig. 4, the piston is preferably made up of two parts screwed together at 19. The lower portion 16 of the piston is of such diameter that it fits snugly in the axial opening in the base plug 11 but with sufficient clearance to permit axial movement of the piston relative to the base plug. It is important that the fit between the lower portion 16 of the piston and the base plug 11 be sufficiently tight to retain a combustion-retarding fluid 20, such as water, and prevent the fluid from leaking out of the bottom of the cylinder. The upper portion 17 of the piston is considerably smaller in diameter than the lower portion 16. The annular space 21 between the upper portion of the piston and the opening in nozzle 14 serves a purpose which will be explained below.

A sample-supporting disc 22 is mounted on the piston at the lower end of its upper portion 17 and is retained in place by shoulder 17a and by the upper end of pipe spacer 18a. Powder samples 23 are mounted on the upper surface of the disc 22 by means of worm head trap rods 24 which are attached to disc 22 by screw threads or other suitable means. The diameter of disc 22 is smaller than the inner diameter of the casing 10 so that the disc fits loosely in the cylinder. A disc 25, which also fits loosely within the cylinder 10, is mounted on the piston at the upper end of its lower portion 16 and is retained in place by shoulder 16a and by pipe spacer 18a. This disc may be perforated, if desired, and serves a purpose which will be explained below.

In assembling the device, the base plug 11 is screwed into place in the lower end of cylinder 10, and the cylinder is then placed upright on a heavy plate having a hole through which the piston may pass. The base plug 11 is stoppered and the fluid 20 is poured in to a level between discs 22 and 25, after which the piston assembly, together with the powder to be tested, is placed in the chamber of the cylinder, and the nozzle holder 12 with the nozzle contained therein is screwed into the upper end of cylinder 10. The

electric squib wires (not shown) for igniting the powder sample are passed out through the annular space 21.

The operation of the device will now be explained. When the powder sample 23 is ignited, the gas pressure in chamber 10a causes the piston and the elements carried by it to move downwardly relative to the casing 10, due to the fact that the cross sectional area of the lower portion 16 of the piston is greater than the cross sectional area of the upper portion 17 of the piston. As the disc 25 moves downwardly with the piston, the fluid 20 flows around it and through the perforations in the disc, resulting in a retarding of the movement of the piston. The rate of movement of the piston can be varied by changing the diameter of disc 25 and by changing the number and size of the perforations in the disc. The speed of movement of the piston is also governed by the difference in the cross sectional areas of portions 16 and 17, by the inertia of the system, and by frictional forces. Variation of the speed of movement of the piston varies the length of time during which the sample burns, as will be further explained below. The faster the piston moves, the shorter will be the length of time during which the sample burns, and vice versa.

As the piston moves downwardly, its upper portion moves out of nozzle 14 until the upper end of the piston clears the base of the nozzle, at which time the gases under compression in chamber 10a suddenly rush out of the nozzle, and the resulting fall of pressure extinguishes the burning powder. By this time, the powder has moved down to the water or other fluid 20 and is prevented from reigniting by being plunged into the fluid. If at any time during the burning of the sample 23, the gas pressure in the device exceeds a predetermined pressure, usually around 10,000 pounds per square inch, the shear ring 13 will give way and nozzle 14 will be blown out of the nozzle holder 12. If desired, a sleeve (not shown) may be provided between the nozzle and the nozzle holder so as to avoid damage to the nozzle in case the nozzle is blown out.

An important feature of the invention is the provision of means for closely simulating conditions existing in actual use of the explosive being tested. The pressure existing in chamber 10a is controlled by the area of the annular space 21 surrounding the upper end 17 of the piston. If the area of the annular space is increased, the pressure will decrease and vice versa. By making the area of the annular space 21 equal to the nozzle area of a given jet propelled device, pressures may be generated in the chamber 10a of the same magnitude as those produced in the jet propelled device in which the explosive is to be used as a propellant, and may be maintained at the equilibrium pressure for the desired length of time.

It will be obvious from the above description that the conditions under which the sample is tested may be controlled as desired by varying the clearance between the upper portion 17 of the piston and the inner walls of the nozzle, that is, the area of annular space 21, to regulate the pressure in the chamber, and by controlling the rate of movement of the piston by means of the dash pot, including disc 25 and the liquid 20, so as to vary the time during which the sample is permitted to burn.

We claim:

1. A device for testing explosive compositions,

which comprises a combustion chamber for burning a sample under pressure, means for suddenly releasing said pressure after a predetermined length of time to extinguish the burning sample, a combustion-retarding fluid in said chamber, and means for submerging the residue of the sample in said fluid to secure it against reignition.

2. A device for testing explosive compositions, which comprises a combustion chamber for burning a sample in a limited space under pressure, means for suddenly releasing said pressure after a predetermined length of time to extinguish the burning sample, a combustion-retarding fluid in said chamber, means for submerging the residue of the sample in said fluid to secure it against reignition, and safety means for releasing said pressure when it exceeds a predetermined limit.

3. A device for producing a partially burned explosive sample, which comprises a cylinder, a combustion-retarding fluid partially filling the cylinder, a plug mounted in the lower end of said cylinder and having an axial passage, a nozzle mounted in the upper end of said cylinder, a piston in said cylinder extending into said nozzle with a substantial clearance and fitting closely in said plug passage, said piston being of larger cross sectional area at the plug end than at the nozzle end, a disc on said piston near the end which extends into the plug and normally confining the fluid between the disc and the plug, and a sample carrying disc mounted on said piston and disposed in a combustion chamber between said first disc and the nozzle, the piston being operable by combustion pressure in said chamber to withdraw the upper end of the piston from the nozzle and cause said first disc to displace a portion of the fluid into the chamber.

4. A device for producing a partially burned explosive sample, which comprises a cylinder, a combustion retarding fluid partially filling the cylinder, a plug mounted in the lower end of said cylinder and having an axial passage, a nozzle mounted in the upper end of said cylinder, a safety shear ring holding said nozzle whereby said nozzle may be blown out of the cylinder when the pressure in the cylinder exceeds a predetermined limit, a piston in said cylinder extending into said nozzle with a substantial clearance and fitting closely in said plug passage, said piston being of larger cross sectional area at the plug end than at the nozzle end, a disc on said piston near the end which extends into the plug and normally confining the fluid between the disc and the plug, and a sample carrying disc mounted on said piston and disposed in a combustion chamber between said first disc and the nozzle, the piston being operable by combustion pressure in said chamber to withdraw the upper end of the piston from the nozzle and cause said first disc to displace a portion of the fluid into the chamber.

5. An explosive testing device comprising a cylindrical casing having an annular plug at each end thereof, a combustion-retarding fluid in the casing, a piston having its lower end of greater cross sectional area than its upper end, said piston fitting loosely within the upper plug and fitting sufficiently tightly within the lower plug to retain said fluid above said plug while permitting axial movement of said piston relative to said plug, a disc mounted on the piston so as to lie normally in a combustion chamber defined by said upper plug and said fluid, said disk being adapted to support a sample of the explosive to be tested,

a second disc mounted on the plunger below said first disc so as to function as a dashpot when forced into said fluid, and a safety shear ring supporting said upper plug in the casing, whereby said upper plug is blown out by excessive pressure in the casing.
